(57) **CLAIM**

The ornamental design for a box cover for limit switch, as shown and described.

DESCRIPTION

FIG. 1 is a perspective view of a box cover for limit switch showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken line portion of the figures is included to show portions of the article that form no part of the claimed design. The oblique short lines in FIG. 1 and FIG. 2 are intended to illustrate that the surface is translucent.
